(57) **CLAIM**

The ornamental design for a battery charger housing as shown and described.

DESCRIPTION

1. Battery charger housing

1.1: Perspective

1.2: Perspective

1.3: Front

1.4: Back

1.5: Left

1.6: Right

1.7: Top

1.8: Bottom

FIG. 1.1 is a front top perspective view of a battery charger housing; FIG. 1.2 is a rear bottom perspective view thereof; FIG. 1.3 is a front elevational view thereof; FIG. 1.4 is a rear elevational view thereof; FIG. 1.5 is a left-side elevational view thereof; FIG. 1.6 is a right-side elevational view thereof; FIG. 1.7 is a top plan view thereof; and FIG. 1.8 is a bottom plan view thereof; the broken lines, where present, illustrate portions of the battery charger housing that form no part of the claimed design.

1 Claim, 8 Drawing Sheets
